UNITED STATES PATENT OFFICE.

LEWIS T. WILCOX, OF PEEKSKILL, NEW YORK, ASSIGNOR TO WILCOX PATENTS CORPORATION, OF PEEKSKILL, NEW YORK, A CORPORATION OF NEW YORK.

LIQUID-FUEL BURNER.

Application filed November 20, 1926. Serial No. 149,552.

My present invention relates to a liquid fuel burner and more particularly to the construction of the air distributor. Heretofore, because the positions of the wick and the walls in which the same is contained are sometimes slightly eccentric and because of drafts or irregular air currents the air necessary for the combustion of the fuel is not evenly distributed to the wick, that is at the point where the fuel vaporizes and is burned. The object of my present invention is to overcome these difficulties and in so doing to construct the air distributor member in such a manner that substantially equal and proper amounts of air are supplied at all points of the wick in order to obtain an even and uniform flame and thereby necessarily to obtain a correspondingly uniform distribution of the heat produced by the burner when in use. In carrying out the invention the burner includes an air distributor preferably comprising a cylindrical member, a drum associated therewith to provide substantially annular and concentric spaces between the exterior of the cylindrical member and the inner wall of the burner, together with partition walls dividing the inner annular space into compartments to which the air supply is directed and may enter by passing inwardly through the drum from the outer annular space and by entering at the bottom of the inner annular space. The air directed into each compartment is confined thereto and flows directly therefrom to the point of vaporization and ignition at the upper end of the wick to provide the necessary or required amount of air for substantially perfect combustion of the fuel.

In the drawing Figure 1 is a central longitudinal section illustrating a liquid fuel burner made in accordance with my present invention.

Fig. 2 is a plan of the same.

Fig. 3 is a section on line 3—3, Fig. 1, and

Fig. 4 is a view illustrating the several parts comprising the air distributor before the same are assembled.

Referring to the drawing the liquid fuel burner made in accordance with this invention includes the usual inner and outer burner tubes 10 and 11 respectively between which there is a wick 12 which may be raised and lowered by any of the devices known to the art. The inner tube 10 in a suitable position is provided with an internal flange 13 for

supporting the air distributor as hereinafter described, and the outer tube 11 in a suitable position preferably somewhat below the flange 13 is provided with an external flange 14. This flange 14 cooperates with suitably spaced arms 15 carried by a collar 16 for positioning the collar, the collar being employed to support the casing of the burner in the customary manner.

The air distributor to which the present invention more particularly relates consists of a multiplicity of parts including a cylindrical member 17 in the walls of which there are suitably spaced apertures 18. At the upper or outer end of the cylinder the same is flanged internally as indicated at 19 and so made as to have a centrally disposed opening 20. Fitted on the upper or outer end of the cylindrical member 17 there is a cap or spreader member 21. A short portion of this cap or spreader member is cylindrical as indicated at 22 so as to fit over the upper or outer end of the cylindrical member 17 to which it is suitably connected by indentations 23 or otherwise. The air distributor also includes a drum 24 in the cylindrical body portion of which there are suitably spaced apertures 25. At the upper or outer end the drum is formed with an inverted U shaped flange 26 which is of slightly smaller diameter than the spreader member and is adapted to lie immediately within the upper or outer end of the inner burner tube 10. The air distributor also includes a base member 27. This member has an aperture through its center and is provided with a downwardly extending flange 28 adapted to receive the lower end of the cylindrical member 17. Its outer edge terminates in an inverted U shaped flange 29, (Fig. 2) the inner wall of which is of substantially the same diameter as the outer diameter of the cylindrical portion of the drum 24 so that the drum 24 fits within this outer peripheral flange of the base 27. The outer wall of the flange 29 is of substantially the same diameter as the diameter of the inner face of the inner tube 10 so that when the air distributor is in position the outer wall of the flange 29 of the base member rests upon the internal flange 13 on the inner wall 10 to support the air distributor in its proper position in the burner. That portion of the base member extending between the flange 28 and the peripheral flange thereof is provided with a

100
105
110

series of spaced apertures indicated at 30, and as indicated in the drawing the transverse wall forming part of the inverted peripheral flange 29 of the base member is also provided 5 with spaced apertures as indicated at 31. The base member 27 is suitably connected to the cylindrical member 17, and as illustrated, this connection may be made by suitably spaced indentations indicated at 32.

10 This construction provides for an annular air distributing chamber 33 between the outer surface of the cylindrical member 17 and the inner surface of the drum 24 and also for a concentric annular chamber 34 surrounding 15 the chamber 33 and lying between the outer wall of the drum 24 and the adjacent portion of the inner wall of the inner burner tube 10.

The annular space or chamber 33 constitutes a passage by which the necessary air is 20 caused to pass and to be delivered to the flame to properly support combustion of the fuel and in order to provide an even distribution of the air to all points in the flame this annular chamber is divided into a plurality of sections. 25 This feature is accomplished by the use of a series of wings or partition walls as indicated at 35. The upper edge of each of these walls is inclined to correspond with the inner face of that portion of the spreader 30 member which extends over the annular chamber 33 as indicated at 36, and each of these partition walls adjacent the upper end thereof is furthermore provided with an extension 37 adapted to lie across the upper 35 portion of the flange 26 of the drum member 24. These wings or partition walls may be secured in position in any suitable manner.

As indicated, however, they are not only 40 maintained in position but assist in connecting the drum to the base and the cylindrical member of the air distributor. Each of these wings is provided at its outer edge with a tongue or lug 38 adapted to pass through a slot 39 provided therefor in the wall of the 45 body of the drum 24 and with a tongue or lug 40 at its lower end adapted to pass through a slot 41 provided therefor in that portion of the base between the flange 28 and the flange 29 thereof. These tongues 38 and 40 may be 50 turned down after being passed through the respective slots provided therefor in order to secure the partition walls or wings in place and to assist in connecting the parts of the distributor to one another as hereinbefore 55 stated.

In the structure as hereinbefore described, 60 it will now be apparent that the supply of air passing upwardly into the inner tube 10 of the burner is distributed into several paths, part of the air passes into the cylindrical member 17 and through the apertures 18 therein to the annular chamber 33; another 65 part of the air passes through the apertures 30 directly into the annular chamber; and still another part of the air passes through

the apertures 31 into the annular chamber 34 and through the apertures 25 in the body of the drum 24 and thus into the annular chamber 33. All the air passing into the inner tube 10, therefore, eventually reaches the 70 annular chamber 33 and therein is divided into as many sections as there are compartments created by the partition wall 35, and as the air passes upwardly and then outwardly to the flame the passage of the air in any 75 particular compartment is not influenced by extraneous conditions such as drafts and the like, thereby ensuring an even distribution of the air to all parts of the wick and causing substantially uniform combustion at all 80 points in the flame whereby as will be understood the efficiency of the burner is materially enhanced.

I claim as my invention:

1. In a liquid fuel burner having a pair of 85 burner tubes adapted to receive a wick therebetween, an air distributor comprising a cylindrical member having spaced apertures therein, a drum member having an inverted U-shaped flange at the upper end thereof and a plurality of spaced apertures in the wall thereof, said drum member surrounding a portion of the cylindrical member and providing an annular space between the same and the cylindrical member, there also being 90 an annular space beneath the said inverted U-shaped flange at the upper end of the drum and between the drum and the said burner tubes, a spreader secured to the upper end of the cylindrical member, a base secured to the lower end of the cylindrical member and co-acting with one of the burner tubes to support the air distributor in position, said base having spaced apertures in that portion 105 thereof lying beneath the annular space between the cylinder and the drum and also spaced apertures in that portion thereof at the lower end of the space between the drum and the burner tube, and a plurality of radially placed partition walls in the 110 annular space between the cylindrical member and the drum, each partition wall being in contact at its upper end with the adjacent portion of the spreader member and the inverted U-shaped flange of the drum and connected to both the drum and the base for securing the partition wall in position and maintaining the drum and the base in place 115 relatively to one another.

2. In a liquid fuel burner having a pair of 120 burner tubes adapted to receive a wick therebetween, an air distributor comprising a cylindrical member, a drum member surrounding a portion of said cylindrical member and providing an annular space between the same and the cylindrical member, a base 125 connected to the cylindrical member and co-operating with one of said burner tubes to support the air distributor, and a plurality of partition walls between said cylindrical mem- 130

ber and said drum dividing said annular space into a plurality of independent compartments.

3. In a liquid fuel burner having a pair of burner tubes adapted to receive a wick therebetween, an air distributor comprising a cylindrical member, a drum member surrounding a portion of said cylindrical member and providing an annular space between the same and the cylindrical member, a base connected to the cylindrical member and cooperating with one of said burner tubes to support the air distributor, and a plurality of radial partition walls extending the entire length of said drum member connected to said base and said drum between said cylindrical member and said drum.

4. In a liquid fuel burner having a pair of burner tubes adapted to receive a wick therebetween, an air distributor comprising a cylindrical member, a drum member surrounding a portion of the cylindrical member and providing an annular space between the same and the cylindrical member, a spreader connected to the upper end of the cylindrical member, a base connected to the lower end of the cylindrical member and cooperating with one of said burner tubes to support the air distributor, and a plurality of partition walls between said cylindrical member and said drum extending from said base to said spreader.

5. In a liquid fuel burner having a pair of

burner tubes adapted to receive a wick therebetween, an air distributor comprising a cylindrical member, a drum member surrounding a portion of the cylindrical member and spaced therefrom to provide an annular space between the same and the cylindrical member, a spreader member secured to the upper end of the cylindrical member extending outwardly over and in spaced relation to the upper edge of said drum, and a plurality of partition walls between said cylindrical member and said drum having extensions lying between the upper edge of said drum and the lower surface of said spreader member.

6. In a liquid fuel burner having a pair of burner tubes adapted to receive a wick therebetween, an air distributor comprising a cylindrical member having spaced apertures therein, a drum member having an inverted U-shape flange at the upper end and a plurality of spaced apertures in the wall thereof, a spreader secured to the upper end of the cylindrical member extending over said U-shape flange in spaced relation thereto, and a plurality of partition walls between said cylindrical member and said drum having extensions lying between said U-shape flange and the lower surface of said spreader.

Signed by me this 12th day of November 1926.

LEWIS T. WILCOX.
